UNITED STATES PATENT OFFICE.

THOMAS F. HAWKE, OF LEWISTOWN, PENNSYLVANIA.

BAG-HOLDER.

1,132,181.

Specification of Letters Patent. Patented Mar. 16, 1915.

Application filed April 30, 1914. Serial No. 835,557.

To all whom it may concern:

Be it known that I, THOMAS F. HAWKE, citizen of the United States, residing at Lewistown, in the county of Mifflin and State 5 of Pennsylvania, have invented certain new and useful Improvements in Bag-Holders, of which the following is a specification.

This invention relates to devices for supporting bags and like receptacles while being filled, and has for one of its objects to 10 simplify and improve the construction and increase the efficiency and utility of devices of this character.

Another object of the invention is to provide a device of this character which may 15 be readily adjusted to bags of different lengths and will hold the bag suspended and in open position to receive its contents.

With these and other objects in view the 20 invention consists in certain novel features of construction as hereinafter shown and described and then specifically pointed out in the claims; and in the drawings illustrative of the preferred embodiment of the invention—Figure 1 is a perspective view of the improved device. Fig. 2 is an enlarged section on the line 2—2 of Fig. 1. Fig. 3 is an enlarged perspective view of the ears for 25 supporting the grip devices. Fig. 4 is an enlarged sectional detail illustrating the manner of constructing and applying the feed chute.

Corresponding and like parts are referred to in the following description and indicated 30 in all the views of the drawings by the same reference characters.

The improved device comprises a tubular shell 10 open at the ends, and preferably cylindrical and with vertical sides. The 35 shell 10 is supported by a plurality of legs 11 attached at their upper ends to the upper portion of the shell and inclined outwardly from the same so that the lower rim of the shell is unobstructed to permit the placing 40 of the bag thereover, as hereafter explained.

The legs 11 are preferably tubular, and each leg is provided with an extension rod 45 12 held adjustably in position relative to the legs by set screws 13. By this means 50 the rods may be adjusted to correspond to any inequalities in the ground on which the device is disposed and thus retain the upper receiving end of the member 10 in horizontal position. Extending from the outer

face of the shell 10 at suitable intervals, 55 preferably midway between each pair of the legs 11, are ears 14 arranged in pairs and each provided with an obliquely directed upwardly opening slot 15.

A bag engaging grip device is mounted to 60 swing between each pair of the ears 14, each grip device comprising plates 16—17 having ears through which a pivot pin 18 passes, the terminals of the pin extending beyond the members 16—17 and engaging in the inclined slots 15 of the ears 14. By this means 65 the members 16—17 are swingingly supported, while at the same time may be readily detached by lifting them upwardly to disengage the pivot 18 from the slots. At their 70 lower ends the members 16—17 are directed inwardly as shown at 19—20, the inwardly directed portions overlapping and preferably serrated and forming the gripping element of the clip device. A spring 21 is engaged between the members 17—18 and operating to maintain the upper portions normally extended and the lower portions compressed and overlapping as illustrated in 75 Fig. 2.

The bag to be supported is disposed by its open receiving end over the member 10 and engaged by the serrated portions 19—20 of the members 16—17, the rods 12 having been adjusted so that the bag when suspended 80 from the ground or just reaching the same. By this means the bag is held in open position to receive the contents which are poured through the open upper end of the shell 10. 85 A chute 24 is supported from the shell 10 by a depending lip 22 which engages over the edge of the member 10 and extends downwardly a short distance therein, while bracket devices 23 are connected to the lower 90 side of the chute and bear against the outer surface of the member 10 at a point considerably lower than the point where the lip 22 engages. The chute 24 is provided with 95 vertical guides to conduct the grain or other material into the shell 10 and thence into the bag suspended therefrom.

The improved device is simple in construction, is constructed entirely of metal as light as possible consistent with the strains 100 to which it will be subjected, and may be varied in size to correspond to bags of different capacities.

Having thus described the invention, what is claimed as new is:

In a device of the class described a tubular support, a plurality of ears arranged in 5 pairs and extending radially from said support, each of said ears having an upwardly directed open socket and inclined toward the support, and a bag holding device for each of said pairs of ears having coacting jaws

and a transverse pivot, said pivot being extended at its terminals to detachably engage in the sockets of the ears.

In testimony whereof I affix my signature in presence of two witnesses.

THOMAS F. HAWKE. [L. s.]

Witnesses:

JOHN H. MARKLEY,
CHAS. F. MARKLEY.
